UNITED STATES PATENT OFFICE.

ALBERT C. MENGES, OF GRAND RAPIDS, MICHIGAN, ASSIGNOR TO
WILLIAM HARRISON, OF GRAND RAPIDS, MICHIGAN.

CARBURETER.

No. 805,979.

Specification of Letters Patent.

Patented Nov. 28, 1905.

Application filed December 23, 1904. Serial No. 238,141.

To all whom it may concern:

Be it known that I, ALBERT C. MENGES, a citizen of the United States, residing at Grand Rapids, in the county of Kent and State of Michigan, have invented new and useful Improvements in Carbureters, of which the following is a specification.

This invention relates to a new and useful carbureter, and is especially adapted for the purpose of mixing the air with the vapors of gasolene or similar substances for preparing and feeding the explosive charge to an explosive-engine.

The objects of the invention are, first, to furnish an efficient carbureter for mixing the air and gasolene in order to provide a suitable explosive charge; second, to furnish means for controlling the valves which admit the air into the chamber, mixes the same with the gasolene, and discharges the same into the cylinder of the explosive-engine; third, to furnish a simple and efficient means for operating a plurality of valves at the same time by means of a longitudinally-moving bar carrying suitable cam-surfaces; fourth, to provide means for adjusting the valve-throwing devices separately and collectively; fifth, other objects hereinafter described and claimed. These objects I accomplish by means of the mechanism illustrated in the accompanying drawings, in which—

Figure 1 shows a longitudinal vertical sectional view of a carbureter constructed in accordance with my invention, illustrating the arrangement of the valves and the means for operating the same. This figure is taken on line 44 of Fig. 2. Fig. 2 is a plan view of a carbureter. Fig. 3 is a sectional view on line 22 of Fig. 1, the parts being shown on an enlarged scale. Fig. 4 is a sectional view on line 33 of Fig. 1. Fig. 5 is a plan view of one of the valve-seats. Fig. 6 is a detail view of the cam-surface for lifting the valves, the same showing the form somewhat modified. This is also shown on an enlarged scale for the purpose of illustrating more clearly the method of adjusting these cam-surfaces on the longitudinally-movable bar.

Similar letters refer to similar parts throughout the several views.

A and B are the two halves of the carbureter which form the shell or case. This is my preferred form, although it may be constructed in other forms.

C C C show the openings in the valve-seat 55 for the valve E.

D D, &c., are openings in the valve-seats for the valve F.

C' is an opening in the valve-seat to receive the stem of the valve E. This opening also 60 acts as a guide for the valve-stem.

D' is an opening in the valve-seat which acts as a guide for the valve-stem of the valve F.

E shows the stem and valve of the valve 65 which seats upon the valve-seat having the openings C C, &c., and this valve E is held in position normally by means of the coiled spring E'.

F is the valve which seats upon the seats 70 having the openings D D, &c., and this valve is held normally in position by means of the coiled spring F'.

G is a tube having passages through which the gasolene passes to the carbureter. This 75 part G also furnishes a support for the float-tank, and the lower portion of the part G is shown by n.

H is a needle-valve fitting into the tapering seat H' (shown in Fig. 1) and adapted to close 80 or open the passage which receives the gasolene into the carbureter.

I is a projection on the needle-valve H, against which the spring J abuts for the purpose of holding the needle-valve normally 85 closed.

K is the adjusting-nut on the needle-valve.

L is a bent lever fulcrumed at the point M, the fulcrum M serving as the attachment for rigidly connecting together the levers L and 90 L', which levers are moved by the cam V for the purpose of raising and lowering the needle-valve.

N is a collar upon the bar X and forms an abutment for the coiled spring Z, as shown in 95 Figs. 1 and 2.

P is a pivotal fulcrum of the lever Q, said lever Q being the lever used for raising the valve E, which admits the explosive mixture into the cylinder of the engine.

R is a fulcrum-pivot for the lever S, pivotally connecting said lever S to the case, and R' is the hole into which the pivot R fits.

S is the lever, which lifts the valve F against the action of the spring F' for the purpose of admitting the air into the chamber.

T is the curved portion of the lever S, which engages with the cam W.

U, V, and W are cams secured to the sliding rod X and adjusted thereon, as hereinafter described.

X is a sliding rod or bar upon which are attached the cams U, V, and W, said bar having a longitudinal motion for the purpose of moving the cams into position to open and close the valves E, F, and H.

Y is the turned or rounded portion of the sliding bar X, which is mounted in the journal X', only one of the journals being shown. X' also furnishes an abutment for the spring Z, the bar X being supported in bearings and is moved longitudinally by any suitable means, carrying with it the cams U, V, and W, as above described. Any suitable means may be used for giving the longitudinal movement to the bar X and cams mounted thereon.

a is a cap for holding in place the tubular portion G, and said cap also forms a bearing for the valve-stem of the valve H and an abutment for the spring J.

b is the cover of the float-tank.

d is the float-tank itself.

e is an adjusting-nut on the valve-stem g of the valve l.

i is a stationary sleeve on the float j, which sleeve i surrounds the valve-stem g.

h is an opening through which the gasoline passes to the passage-chamber when the needle-valve is raised, h being shown in Fig. 1.

j is the float.

l is the valve for admitting the gasoline to the tank.

m is a threaded portion of the tank which receives the pipe which conveys the gasoline from some outside source into the tank.

n is the lower or bent portion of the tubular part G and is secured into the wall of the tank-chamber d.

r and r' form a passage-way for the gasoline extending from the tank to the carbureter.

t (shown in Fig. 6) is a modified form of one of the cams.

The cam U is pivoted at u and is adjusted by means of the slot u', a screw or bolt passing through said slot. The cam V is pivoted at the point v and adjusted by means of the adjusting-screw v', passing also through a slot. The cam W is pivoted at w and adjusted by means of a screw passing through the slot w'. In Fig. 6 the slot w' is fully illustrated, also the general form of the cam.

The three cams are all adjusted in a similar manner, being pivoted at the smaller end to the sliding bar X and adjusted at the larger end by means of a slot, a screw, or bolt, and the description of one would serve for the description of the three cams.

In operation the gasoline from the main tank is forced into the tank-chamber by any suitable means and lifts the float j to a position just above the level of the outlet of the gasoline. The sleeve i raises the valve-stem

g by coming in contact with the adjusting-screw e and closes the valve l. The gasoline is then allowed to pass through the channels r r' and comes in contact with and passes through the needle-valve H. When said needle-valve is raised by the cam V, the gasoline passes through the opening h. At the same time the valve F is raised by the cam W, permitting the air to pass into the chamber, mixing the same with the gasoline, and the valve E having been raised the explosive charge passes through the openings CC, &c., into the cylinder of the engine at regular intervals. In Fig. 1 I have shown the passage of the air and explosive charge by means of the arrows 1, 2, 3, and 4.

By my construction the valve-operating mechanism can be adjusted with great accuracy. The three valves are opened and closed by a single action of the longitudinally-sliding rod or bar having the cam-surfaces. Each cam-surface can be adjusted independently for the purpose of accurately adjusting the throw of its corresponding valve, and the inclined surfaces of the cams may be readily changed to suit any required adjustment. By a proper adjustment of the inclines on the sliding bar the valve E and the valve H may be left open while the valve F is nearly closed. This causes a strong suction through the valve H, and when in this position the engine can be started without priming the float or carbureter. By this construction stuffing a box having the needle-valve may be dispensed with, and also screw-threads on the needle-valve are dispensed with.

Having thus described my invention, what I claim to have invented, and desire to secure by Letters Patent, is—

1. In a carbureter, the combination of a shell or case having separated valve-seats therein, valves coöperating with said seats and having stems, the said valves controlling the admission of air and the outlet of the commingled air and gasoline, a gasoline-valve located intermediate of the said valve-seats and valves and regulating the supply of gasoline to the carbureter, movable projecting devices connected to the stems of the valves and located exteriorly of the carbureter, and a longitudinally-slidable rod having cams thereon with which the free extremities of the projecting devices loosely engage, the said projecting devices being normally out of engagement with respect to the cams and automatically returning to normal position when out of engagement with the cams to permit the valves to close.

2. The combination with a carbureter having valves for controlling communication between the several parts of the carbureter and provided with valve-stems projecting exteriorly of the latter, levers attached to the valve-stems and having their free terminals disposed in longitudinal alinement, and a lon-

5 longitudinally-slidable rod carrying a plurality of cams to individually engage the free terminals of the levers, the levers operating to automatically open the valves when engaged by the cams and automatically returning to normal position when released from the cams to close the valves.

3. The combination with a carbureter, of valves controlling communication between the several parts thereof and the admission of gasoline thereto, and provided with exteriorly-projecting valve-stems, and a longitudinally-movable rod carrying a plurality of fixed cam devices which individually engage movable portions of the valve-stems to automatically open the valves, the cams being normally disengaged from the valve-stems.

4. The combination with a carbureter, of inlet and outlet valves therefor having valve-stems projecting exteriorly of the carbureter, a gasoline-valve also having a stem projecting exteriorly of the carbureter between the inlet and outlet valve stems, and a longitudinally-slidable rod carrying a plurality of cams

25 to individually engage portions of the stems of the inlet, outlet and gasoline valves, the valve-stems being normally disengaged from the cams, and each cam provided with means for independently adjusting the same.

5. The combination with a carbureter, of 30 inlet and outlet valves therefor having valve-stems, a gasoline-valve also having a stem, a longitudinally-slidable rod having thereon independent inclined surfaces for operation with the several valves, and a lever for each valve-stem secured to the carbureter and having a free extremity to loosely bear on its corresponding inclined surface, for the purpose of throwing its valve open when the rod is moved longitudinally.

35 In testimony whereof I have hereunto set my hand in presence of two subscribing witnesses.

ALBERT C. MENGES.
